B. W. PRALL

RADIOSWITCH

Filed May 16, 1923

Fig. 1.

Fig. 4.

UNITED STATES PATENT OFFICE.

BRYAN W. PRALL, OF NEW YORK, N. Y.

RADIOSWITCH.

Application filed May 16, 1923. Serial No. 639,421.

To all whom it may concern:

Be it known that I, BRYAN W. PRALL, a citizen of the United States, and a resident of the city of New York, West New Brighton, borough of Richmond, in the county of Richmond and State of New York, have invented new and useful Improvements in Radioswitches, of which the following is a full, clear, and exact description.

16 This invention relates to switches of the plug and jack type primarily designed for use with radio apparatus.

With the wide introduction of radio receiving sets provided with vacuum tubes for 15 amplifying the waves of radiant energy of radio-frequency and audio-frequency it becomes necessary to provide means for consecutively connecting any desired number of tubes into the radio-receiving circuits.

20 The introduction of any desired number of vacuum tubes into the circuits of the radio-receiving set may be accomplished when making the original assemblage, but if it becomes necessary or desirable to cut down the 25 number of stages of amplification then the connections have to be rearranged. The rearranging of the connections causes considerable delay and often those unskilled in the art find it impossible to reestablish their 30 radio-receiving circuits after they have been disconnected in order to rearrange the connections to eliminate or introduce vacuum tubes.

The general object of this invention is 35 the provision of a cheap, simple and efficient radio switch provided with means for introducing any desired number of vacuum tubes into radio-receiving circuits in order to give any desired number of stages of amplification of the received waves of radiant energy by the adjustment of a plug.

This object is accomplished by mounting on a frame a plurality of pairs of short and long line springs spaced from one another 45 by insulating members, each pair of short springs being associated with a pair of long springs, and providing a plug having two contact members insulated from each other for establishing connections with any pair 50 of long springs, and an insulating member for operating pairs of long springs to force them into contact with corresponding members of the pair of short springs associated therewith.

55 This and other objects of the invention

will be more clearly understood from the following detailed description and accompanying drawings.

Figure 1 is a side elevation of the radio switch showing its construction;

60 Figure 2 is a side elevation of the radio switch showing the plug associated with the first pair of long line springs, establishing connections therewith;

Figure 3 is a side elevation of the radio switch showing the plug operating the first pair of long line springs, forcing them into contact with the corresponding members of the associated pair of short line springs and establishing connections with the second 70 pair of long line springs;

Figure 4 is a diagram showing how the radio switch might be connected in a radio receiving circuit in order to introduce different stages of amplification into the receiving circuit.

75 Referring to the above-mentioned drawings, the invention includes a frame 10 on which a plurality of spaced long and short springs 11 to 20, inclusive, are mounted. 80 These springs are mounted in pairs and are spaced and insulated from one another by insulating blocks 21. The long springs 15 to 20, inclusive, are made of varying lengths and have provided on their lower ends in- 85 turned portions which are engaged by a plug 23. The short springs 11 and 12 are associated with the springs 15 and 16, re- 90 spectively, while the springs 13 and 14 are associated with the long springs 17 and 18, 95 respectively. In mounting the springs 15 to 20, inclusive, one member of each pair is positioned so as to extend beyond the other member of the pair. Contact members 22 are mounted on the springs 11 to 18, inclu- 100 sive, for establishing contact between the corresponding members of the different long and short springs when the long springs are 105 operated. A sleeve 24 is mounted in the frame 10 for directing the plug 23 between the long springs 15 to 20, inclusive. The plug 23 includes two contact members 25 and 27, insulated from one another by the member 26. These contact members 25 and 27 would be normally connected by conductors to any head set. An insulating sleeve 28 is mounted on the lower ends of the contact members 25 and 27.

110 In the operation of the switch, when the plug is projected through the sleeve 24 into

engagement with the springs 15 and 16, contact member 25 contacts with the spring 16, and the contact member 27 contacts with the spring 15. When the plug is projected another step the insulating sleeve 28 is projected between the springs 15 and 16 and the contact member 25 contacts with the spring 18 while the contact member 27 contacts with the spring 17. The projecting of the sleeve 28 between the springs 15 and 16 forces them outward, establishing contact with the springs 11 and 12, respectively, through the contact members 22. On forcing the plug a third step the sleeve 28 is projected between the springs 17 and 18 and the contact member 25 contacts with the spring 20 while the contact member 27 contacts with the spring 19. The springs 15 and 16 remain in contact with the springs 11 and 12, respectively, while the springs 17 and 18 are forced outward into contact with the springs 13 and 14, respectively. The reverse operation takes place when the plug is pulled outward step by step.

Figure 4 shows a diagram illustrating connections that might be made to use the above-described switch for introducing any desired number of stages of amplification into a radio receiving circuit. The pair of springs 11 and 12 is connected by conductors 35 and 36 to the terminals of the primary of the transformer 41 while the springs 15 and 16 are connected by conductors 29 and 30 to the plate of the vacuum tube 31 and the positive pole of the battery 42. Conductors 37 and 40 connect the springs 13 and 14 to the terminals of the primary of the transformer 43, while conductors 38 and 39 connect the springs 17 and 18 to the positive terminal of the battery 42 and the plate of the vacuum tube 33, respectively. The inner springs 19 and 20 are connected by the conductors 44 and 45 to the positive pole of the battery 42 and the plate of the vacuum tube 34, respectively. When the plug is projected between the springs 15 and 16 so that the contact member 25 contacts with the spring 16 and the contact member 27 with the spring 15 the tube 31 is introduced into the receiving circuit, giving one stage of amplification or detection. As the plug 23 is moved step by step the vacuum tubes 33 and 34 are introduced into the circuit, finally giving three stages of amplification or one stage of detection and two stages of audio-amplification.

I would state in conclusion that while the illustrated example constitutes a practical embodiment of my invention I do not limit myself strictly to the exact details herein illustrated since manifestly the same can be considerably varied without departing from the spirit of the invention as defined in the appended claims.

Claims:

1. A radio switch, comprising a frame, a plurality of pairs of short and long line springs mounted on the frame, each pair of short line springs being associated with a pair of long line springs, and means for successively establishing electric connection with the pairs of long line springs and for operating the pairs of long line springs to project them into contact with corresponding springs of the pair of short line springs with which they are associated. 75
2. A radio switch comprising a frame, a plurality of pairs of short and long line springs mounted on the frame, each pair of short line springs being associated with a pair of long line springs, a plug for successively establishing electrical connection with the pairs of long line springs to establish electric circuits, and means carried by the plug for operating the long line springs to project them into contact with corresponding short line springs to maintain said circuits established as the plug advances step by step. 80
3. A radio switch, comprising a frame, a plurality of pairs of short and long line springs mounted on the frame, each pair of short line springs being associated with a pair of long line springs, and means for establishing electrical connection with any pair of long line springs and for operating pairs of long line springs to project them into contact with corresponding springs of the pair of short line springs with which they are associated. 85
4. A radio switch, comprising a frame, a plurality of pairs of short and long line springs mounted on the frame, each pair of short line springs being associated with a pair of long line springs, and a plug for operating said line springs comprising two insulated contact members for establishing connection with any pair of long line springs and an insulating member for operating pairs of long line springs to project them outward into contact with corresponding short line springs to establish electric circuits. 105
5. A radio switch, comprising a frame, a plurality of pairs of short and long line springs mounted on the frame, each pair of short line springs being associated with a pair of long line springs, said pairs of long line springs being so positioned that the end of one member of each pair extends beyond the other member, and a plug having two insulated contact members for establishing connections with any pair of long line springs and means for operating pairs of long line springs to force them into contact with corresponding members of the short line springs to establish electric circuits. 115
